UNITED STATES PATENT OFFICE.

HOWARD M. BARBER, OF WESTERLY, RHODE ISLAND, ASSIGNOR TO C. B. COTTRELL & SONS COMPANY, OF WESTERLY, RHODE ISLAND, A CORPORATION OF DELAWARE.

CONTROLLING MEANS FOR THE TRAVELING OFFSET WEB OF MULTICOLOR-PRINTING PRESSES.

Application filed October 31, 1925. Serial No. 65,977.

In multi-color web perfecting printing presses where a traveling offset web is led around the impression cylinder of the second printing unit under the printed web, it 5 has been difficult to obtain clean and sharp printing because of the tendency of the traveling offset web to travel at a different speed than the printed web as the printed web is fed around the impression cylinder 10 by its contact with the printing surfaces of the plate cylinders.

In practical printing the surfaces of the plates are located below the bearer surfaces of their cylinders so that the surface speed 15 of the bearers is slightly greater than the surface speed of the printing plates.

I have discovered that if the traveling offset web be positively fed at the speed of the printed web, i. e., the surface speed of the 20 plates, clean and sharp printing will be obtained as the tendency of the offset web to creep or crawl to change its relation to the printed web is entirely eliminated.

A practical embodiment of my invention 25 is represented in the accompanying drawings, in which the plate and impression and cylinders of the second printing unit are denoted by 1, 2, 3, 4 and 5. The printed web is denoted by 6 and the traveling offset web by 7, which offset web is shown as leading from the supply roll 8 around the impression cylinder 5 to the take-up roll 9.

The means which I have shown for positively feeding the traveling offset web at the 30 speed of the printed web is as follows:

A plurality of offset web feeding rolls, in the present instance three rolls 10, 11 and 12 are positively driven through their gears 13, 14 and 15, and intermediate gear 16

from a gear 17 of the impression cylinder 40 5 at a surface speed equal to the surface speed of the plates on the plate cylinder which is the same as the speed of the printed web. These offset web feeding rolls will entirely eliminate any tendency on the part 45 of the offset web to change its relation to that of the printed web.

What I claim is:—

1. In a multi-color web perfecting printing press, a printing unit, a traveling offset 50 web, and means for positively feeding the offset web into the printing unit at the speed of the printed web.

2. In a multi-color web perfecting printing press, a printing unit, a traveling offset 55 web, and means driven from the impression cylinder for positively feeding the offset web into the printing unit at the speed of the printed web.

3. In a multi-color web perfecting printing press, a printing unit, a traveling offset web, and offset web feeding rolls driven 60 at the printing surface speed of the plate cylinders for positively feeding the offset web into the printing unit at the speed of 65 the printed web.

4. In a multi-color web perfecting printing press, a printing unit, a traveling offset web, and offset web feeding rolls driven 70 from the impression cylinder at the printing surface speed of the plate cylinders for positively feeding the offset web into the printing unit at the speed of the printed web.

In testimony, that I claim the foregoing 75 as my invention, I have signed my name this 28th day of October, 1925.

HOWARD M. BARBER.
